UNITED STATES PATENT OFFICE

172,795

SHOWCASE

Stanley L. Kaufman, Burlington, Vt.

Application February 15, 1954, Serial No. 29,023

Term of patent 7 years

(Cl. D80—11)

To all whom it may concern:

Be it known that I, Stanley L. Kaufman, a citizen of the United States, residing at Burlington, in the county of Chittenden and State of Vermont, have invented a new, original, and ornamental Design for a Showcase, of which the following is a specification, reference being had to the accompanying drawing, forming part thereof.

I claim:

The ornamental design for a showcase, as shown.
